[57] **ABSTRACT**
Acetylene sulfonyl compounds of the formula R—C≡C—(CH₂)_n—SO₂—R' wherein R, R' and n are defined in claims are found to be useful as hardeners for the gelatin films of light-sensitive silver halide photographic materials. Synthesis and use of these compounds also are disclosed.

6 Claims, No Drawings

SILVER HALIDE PHOTOGRAPHIC ELEMENT
CONTAINING AN ACETYLENE SULFONYL
COMPOUND AS HARDENER

This invention relates to a hardener for the gelatin 5 films of a light-sensitive silver halide photographic material, said hardener comprising a compound of the general formula,

wherein R' is a lower alkyl group or a phenyl or alkyl- 10 phenyl group; R is a hydrogen atom, a lower alkyl group or a phenyl, alkylphenyl, alkoxyphenyl or halo- phenyl group; and n is zero or 1.

Generally, a light-sensitive silver halide photographic material is prepared by forming various layers such as 15 silver halide photographic emulsion layer, filter layer, inter layer, protective layer, sub layer, backing layer, etc. on a suitable support such as glass, paper or synthetic resin film. These layers are composed mainly of gelatin, so that the physical properties of said layers are dependent chiefly upon the physical properties of gelatin. However, gelatin itself is low in melting point, water-swelling and low in mechanical strength, and these properties are not desirable, or rather to say, are fatal drawbacks for the layers constituting a light-sensitive 20 silver halide photographic material.

In view of the above, many attempts have heretofore been made to improve the physical properties of gelatin by treatment with various hardeners. These hardeners, however, have such photographic defects as being 25 strong in desensitizing action and high in fog-forming action and, in the case of color photographic emulsions, bring about such drawbacks that they disturb the color developability of couplers or are too vigorous in hardening action to make the production of light-sensitive photographic materials difficult. Further, due 30 particularly to the recent tendency of quick development and the adoption of automatic developing machines, the physical properties of films have come to be required more strong.

We made extensive studies on hardeners capable of giving gelatin films having such strong physical properties as to be suitable for the above-mentioned quick and automatic treatment of light-sensitive photographic materials to find that acetylene sulfones having the aforesaid general formula display excellent hardening actions without deteriorating the properties of photographic materials.

Examples of the compounds having the aforesaid 35 general formula are as follows:

1. Ethyl 1-pentylnyl sulfone

b.p. 96-97°C/
10⁻³mmHg

2. Phenyl 1-propynyl sulfone

m.p. 68-69°C

3. p-Tolyl 1-propynyl sulfone

m.p. 96-98°C

4. Phenyl 2-propynyl sulfone

55

60

65

m.p. 93°C

5. p-Tolyl 2-propynyl sulfone

m.p. 95-97°C

6. Phenyl 2-butynyl sulfone

m.p. 63.5°C

7. Methyl phenylethynyl sulfone

m.p. 66-67°C

8. p-Tolyl phenylethynyl sulfone

m.p. 80-81°C

9. p-Tolyl p-tolylethynyl sulfone

b.p. 154-155°C/
10⁻⁴mmHg

10. p-Tolyl p-bromophenylethynyl sulfone

m.p. 107-108°C

11. p-Tolyl m-methoxyphenylethynyl sulfone

b.p. 165-167°C/
10⁻⁴mmHg

12. Phenyl 3-phenyl-2-propynyl sulfone

m.p. 116-117°C

The above-mentioned compounds may be synthesized by oxidizing corresponding acetylene sulfides according to, for example, the method disclosed in Bull. Soc. Chim. Fr., 1966, 3024. Procedures for synthesis of the compounds are set forth below as reference examples.

REFERENCE EXAMPLE 1

To a solution of 7.53 g of ethyl 1-pentylnyl sulfide in 100 ml. of methylene chloride is added a 0° to 5°C. a solution of 48.8 g of m-chloroperbenzoic acid in 400 ml. of methylene chloride, and the resulting mixture is stirred at 0° to 5°C. for 4 hours. The reaction mixture is diluted with 1.0 l. of ether, and the dilution is washed with a saturated aqueous sodium bicarbonate solution and water in this order and then dried with anhydrous sodium sulfate. Subsequently, the solvent is removed by distillation, and the residue is subjected to distillation under highly reduced pressure to obtain 5.11 g of ethyl 1-pentylnyl sulfone, yield 54.3%, b.p. 96°-97°C./-10⁻³mmHg.

REFERENCE EXAMPLE 2

To a solution of 40.2 g of 1-propynyl p-tolyl sulfide in 600 ml. of glacial acetic acid is added 33.8 g of 30% hydrogen peroxide, and the resulting mixture is heated at 50° to 60°C. for 2 hours. The reaction mixture is poured into 5 liters of ice water, and deposited crystals are recovered by filtration to obtain 42.4 g of p-tolyl 1-propynyl sulfone in the form of prisms, yield 88.2%, m.p. 90°-91°C.

The compound having the aforesaid general formula may be incorporated as a gelatin film hardener into any of gelatin-containing layers constituting a light-sensitive photographic material, e.g. the sub layer, emulsion layer, inter layer, protective layer and backing layer, whereby the film can be hardened. Alternatively, a photographic film bearing the above-mentioned layers may be hardened by immersing the film in a solution of the said compound, or by dipping the film in any of the baths containing the said compound at the time of development treatment. The hardener of the present invention may be used in combination with a known inorganic hardener such as chromium alum or chromium trichloride, or a known organic hardener such as formalin, glyoxal, acrolein or the like.

In incorporating into the gelatinous layers of a light-sensitive silver halide photographic material, the hardener of the present invention is used ordinarily in the form of a solution in water or methanol, but may also be used in the form of a solution in one or more of organic solvents such as dimethylformamide and the like. The amount of the hardener to be incorporated is preferably in the range of 1 to 20% by weight based on the weight of gelatin in the coating liquid. In case the hardener is desired to be incorporated into a light-sensitive silver halide emulsion layer, it is preferable to incorporate the hardener after the second ripening of said silver halide emulsion. In this case, the hardener of the present invention may be used in combination with other ordinary additives for said photographic emulsion such as, for example, stabilizers, coating aids, sensitizers or sensitizing dyes. Further, the photographic emulsion used may have been subjected to chemical sensitization by use of gold or sulfur, and may have been incorporated with a coupler.

When applied in the above manner to a light-sensitive silver halide photographic material, the hardener of the present invention displays excellent hardening effect without adversely affecting the fog, sensitivity and the like photographic properties of the photographic emulsion. Further, even if the light-sensitive photographic material incorporated with the hardener is stored for a long period of time, the hardener provides effective stability without giving any detrimental effect to the photographic emulsion, and exhibits excellent hardening effect even when the photographic material is subjected to high temperature development and automatic treatment.

The present invention is illustrated in further detail below with reference to examples, but it is needless to say that the invention is not limited only to these, and various modifications are possible within the scope of the invention.

EXAMPLE 1

A silver iodobromide emulsion for photographic negative, which emulsion contains 3 mole% of silver iodide was charged with a gold sensitizer and then subjected to second ripening. Subsequently, the emulsion was divided into 4 portions, and one portion was coated as it was on a support to prepare a control sample, while the remaining 3 portions were individually incorporated with each of methanol solutions of the previously exemplified compounds (2), (7) and (10) and then coated on a support to prepare samples of the present invention.

These samples were individually stored at 55°C. for 3 days, and at 50°C. and RH 80% for 3 days. The thus stored samples and the fresh samples (which were immediately after coating on supports) were individually immersed in pure water, and the temperature at which each sample was dissolved on the film surface was measured. On the other hand, the stored samples were immersed in a 3% solution of sodium carbonate monohydrate at 50°C., and the time required for each sample to initiate the dissolution of its film surface was measured. Further, the samples were subjected to sensitometry to measure the values of relative speed and fog of the photographic emulsions. The results obtained were as set forth in Table 1.

TABLE 1

Sample	Amount of hardener per 10 g. of gelatin (mg.)	Hardening characteristics							
		Sensitivity characteristics of emulsion			Temperature required for dissolution in pure water (°C.)			Time required for initiation of dissolution in alkali (sec.)	
		Fog	Relative speed	Immediately after coating	After storage at 55°C. for 3 days	After storage at 50°C. and RH 80% for 3 days	Immediately after coating	After storage at 55°C. for 3 days	After storage at 50°C. and RH 80% for 3 days
Control sample		0.20	100	31	32	34.4	1.8	1.9	2.0
Sample incorporated with exemplified compound (2)	300	0.16	98	(a)	(a)	(a)	130	180	210
Sample incorporated with exemplified compound (7)	300	0.15	96	(a)	(a)	(a)	91.0	200	600
Sample incorporated with exemplified compound (10)	300	0.17	98	60	(a)	(a)	75.0	165	168

* Above 65.

As is clear from the above table, the samples according to the present invention had no desensitizing action, successfully inhibited the fog and displayed excellent hardening effects.

EXAMPLE 2

The same photographic emulsion as in Example 1 was subjected to second ripening and then charged with a color coupler 1-(4'-phenoxy-3'-sulfophenyl)-3-heptadecyl-5-pyrazolone. Thereafter, the emulsion was divided into 4 portions, and one portion was coated as it was on a support to prepare a control sample, while the remaining 3 portions were individually incorporated with each of aqueous solutions of the previously exemplified compounds (3), (6) and (11) and then coated on supports to prepare samples of the present invention.

These samples were individually measured to determine hardening effect in the same manner as in Example 1. Further, the samples were subjected to sensitometry by developing the samples with a color developer containing diethyl-p-phenylenediamine and effecting ordinary bleaching, fixing and water-washing treatments. The results obtained were as set forth in Table 2, in which the speed is represented by a relative speed.

EXAMPLE 3

A high speed light-sensitive silver iodobromide emulsion for roentgenography, which contained 3 mol % of silver iodide was subjected to ordinary chemical ripening, and then charged with 100 ml. per liter of the emulsion of 5-methyl-7-hydroxy-s-triazolo(2.5-a)pyrimidine as a stabilizer and 2 g per liter of the emulsion of saponin as a coating aid. Subsequently, the emulsion was divided into seven portions, and one portion was coated as it was on a cellulose triacetate support to prepare a control sample, while the remaining six portions were individually coated to prepare samples of the present invention.

These samples were exposed according to the method regulated in Japanese Industrial Standards, subjected to high temperature quick development at 30°C. for 1 minute and 30 seconds, at 35°C. for 40 seconds, and at 40°C. for 25 seconds by use of a strongly alkaline roentgen film-developing solution containing 1-phenyl-3-pyrazolidone and hydroquinone, and then measured in speed and fog. Further, the sample were measured in hardening effects according to the same procedures as in Example 1.

Separately, the films were measured in surface strength in the following manner: Each sample was dipped for 2 minutes in a 3% sodium carbonate (mono-

TABLE 2

As is clear from the above table, the samples incorporated with the hardeners of the present invention effectively inhibit fog even at the time of high temperature quick development, and display excellent hardening effects without any detrimental influence on speed of the emulsion. Moreover, they are high in film surface strength and do not undergo any mechanical damage even when subjected to automatic developing machines.

10 What we claim is:

1. A light-sensitive silver halide photographic material comprising (1) a support, (2) at least one gelatin layer coated on said support, one of said layers containing the silver halide and (3) from 1 to 20% by weight of the gelatin in any of said layers of a hardener which is a compound having the formula

$$R-C\equiv C-(CH_2)_n-SO_2-R'$$
 wherein R' is a lower alkyl, phenyl or alkylphenyl group; R is a hydrogen atom, a lower alkyl, phenyl, alkylphenyl, alkoxyphenyl or halophenyl group; and n is zero or 1.
2. The material according to claim 1 wherein R is methyl, R' is phenyl and n is zero.
- 25 3. The material according to claim 1 wherein R is methyl, R' is p-tolyl and n is zero.
4. The material according to claim 1 wherein R is methyl, R' is phenyl and n is 1.
5. The material according to claim 1 wherein R is phenyl, R' is methyl and n is zero.
- 30 6. The material according to claim 1 wherein R is m-methoxyphenyl, R' is p-tolyl and n is zero.
